[57] CLAIM

The ornamental design for a combined hunting knife and sheath, or similar article substantially, as shown and described.

DESCRIPTION

FIG. 1 is a side elevational view of a combined hunting knife and sheath, or similar article, showing my new design, the opposite side being a mirror image thereof; FIG. 2 is an edge elevational view of the left side of FIG. 1;

FIG. 3 is an edge elevational view of the right side of FIG. 1;

FIG. 4 is a top view of FIG. 1;

FIG. 5 is a bottom view of FIG. 1;

FIG. 6 is a top view of the sheath of FIG. 1 with the knife removed;

FIG. 7 is a side elevational view of the knife of FIG. 1 removed from the sheath, the opposite side being a mirror image thereof;

FIG. 8 is an edge elevational view of the left side of FIG. 7;

FIG. 9 is an edge elevational view of the right side of FIG. 7; and

FIG. 10 is a bottom view of FIG. 7.
